FIG. 2

FIG. 3

FIG. 4

FIG. 5

FIG. 6

FIGURE 1 is a face view of a set of sign panel letters showing my new design, the letters A-L being shown in this view;

FIG. 2 is a similar view of the letters M-X;

FIGURE 3 is a similar view of the letters Y and Z, the symbol & and the numerals 1-9;

FIGURE 4 is a similar view showing the zero symbol, punctuation symbols and the 1/2 numeral;

FIGURE 5 is a representative of the rear view of any one of the letters, numerals and symbols; and

FIGURE 6 is a side edge view thereof.

The design is characterized by the background of each letter having an embossed, metallic-appearing finish of contrasting color to the letter, which has a smooth surface with distinctive outline edging, and by breadth of width of letters, by breadth of width of the lines forming the letters and by the generous slant of the letters relative to the vertical.

I claim:

The ornamental design for a set of sign panel letters, numerals and symbols, as shown and described.
